UNITED STATES PATENT OFFICE.

WALTON DOUGLASS MILAM, OF EL PASO, TEXAS.

MATTRESS.

Application filed June 15, 1923. Serial No. 645,637.

To all whom it may concern:

Be it known that I, WALTON D. MILAM, a citizen of the United States, residing at El Paso, in the county of El Paso and State 5 of Texas, have invented a new and useful Mattress, of which the following is a specification.

This invention relates to mattresses for beds, cots and the like.

10 The object of the invention is to provide a mattress so constructed that a person may sleep on his stomach or side and be completely covered up and yet have ample fresh air provided for breathing avoiding any 15 twisting of the head and rendering the bed much more comfortable.

Another object of the invention is to provide an adjustable headrest for a mattress equipped with breathing openings.

20 Another object is to provide a mattress having toe receiving openings, the location of which may be varied to suit persons of different lengths.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed may be made without departing from the spirit of the invention.

In the accompanying drawings:

35 Figure 1 represents a side elevation of a mattress embodying one form of this invention.

Fig. 2 is a top plan view showing a double bed mattress of this character.

40 Fig. 3 is a detail sectional view showing one form of breathing opening.

Fig. 4 is a similar view showing another form.

Fig. 5 is a side elevation of a mattress 45 showing a slightly different form of the invention with the foot receiving apertures arranged for a short person.

Fig. 6 is a similar view with the pillow section omitted and the foot section arranged for tall persons, and

Fig. 7 is a similar view with an adjustable headrest and the foot sections arranged to accommodate an extremely tall person.

In the embodiment illustrated in Figs. 1 55 and 2, a double bed mattress 1 is shown having a hingedly connected adjustable head

support or pillow 2 at one end and a plurality of longitudinally adjustable transversely extending foot sections 3 any desired number of which may be employed, three being 60 here shown which are mounted on a pad 4 formed at the foot of the mattress and which are designed to prevent the toes of the sleeper from contact with the bed spring. 65

The foot sections 3 are of a width sufficient to leave a space 5 when adjusted to receive the toes of the sleeper when resting on his stomach and these sections may move longitudinally on the pad 4 so that the space 70 5 may be formed either between the section or between the inner section and the foot of the mattress proper to accommodate persons of different heights.

A removable section 6 is shown midway 75 the length of the mattress and is curved at its opposite ends so that when removed, the space left will comfortably receive the abdomen of stout people. A similar section 7 is arranged at the upper end of section 6 80 and is designed to be removed when the bed is to be used by a woman having a large bust so that she may comfortably lie on her face, the bust being received in the recess formed by the removal of section 7. 85

The headrest or pillow 2 is provided with an opening 8 which extends through the pillow from the top to the bottom, being preferably arranged at an oblique angle as shown in Fig. 2, the bottom of which is 90 larger than the top, so that a person lying on his stomach may have his face positioned over this opening for breathing purposes. The double bed mattress shown in Fig. 2 of course, is designed to accommodate two people and the various parts are duplicated but obviously it may be made in a single bed form. 95

In Figs. 3 and 4, the breathing openings are shown of slightly different form the 100 opening 8^a of Fig. 3 being truncated cone-shaped flaring toward its lower end while in Fig. 4 the upper portion of the opening is flared as shown at 8^b and the lower portion 8^c corresponds in shape to the opening 105 shown in Fig. 3.

In Fig. 5, the headrest 2^a is shown detachable from the body of the mattress and is equipped with the breathing opening 8 similar to those in the headrest shown in the other figures. In this form of the invention, the foot sections 3 are so adjusted that 110.

the space 5 is formed between the inner section 3 and the central section to accommodate a slightly taller person than the one for which the mattress shown in Figs. 1 and 5 2 is designed.

In Fig. 6, the mattress 1^a is exactly like that shown in Fig. 5 except that the headrest 2^a is dispensed with, the upper end of the mattress being apertured as shown at 8^a 10 to receive the face of the user to permit comfortable breathing while the sections 3 at the foot are changed to accommodate a taller person.

In Fig. 7, the headrest 2^b is similar to that shown in Fig. 1 except that the shape of the breathing opening is varied and the foot sections 3 are arranged at the extreme 15 inward limit to accommodate an extremely tall person.

From the above description it will be obvious that the mattress constructed as herein shown and described may be used either as an ordinary mattress when the sections are in place or the sections may be removed 20 to accommodate stout persons in the manner above set forth.

Various changes in the form, shape, proportion and other minor details of construction

may be made without departing from the spirit or sacrificing any of the advantages of the claimed invention. 30

I claim:—

1. A mattress having a breathing opening extending through the upper portion thereof, the lower portion of the mattress being equipped with a plurality of longitudinally adjustable sections to provide a foot receiving opening, said sections being slidable to vary the position of said opening. 35

2. A mattress having a breathing opening extending through the upper portion thereof, the lower portion of the mattress being equipped with a plurality of longitudinally adjustable sections to provide a foot receiving opening, said sections slidable to 40 vary the position of the opening, said mattress having a pad extending under said sections to protect the toes of the user against contact with the bed spring. 45

In testimony that I claim the foregoing as my own, I have hereto affixed my signature in the presence of two witnesses. 50

WALTON DOUGLASS MILAM.
